W. E. FISHER

BY *John W. Fisher*
ATTORNEYS

UNITED STATES PATENT OFFICE.

WALTER EMILE FISHER, OF NEW IBERIA, LOUISIANA.

OIL-BURNING APPARATUS.

Application filed October 22, 1921. Serial No. 509,515.

To all whom it may concern:

Be it known that I, WALTER EMILE FISHER, a citizen of the United States, and a resident of New Iberia, in the parish of Iberia and State of Louisiana, have invented certain new and useful Improvements in Oil-Burning Apparatus, of which the following is a specification.

My invention relates to oil burning apparatus particularly designed for use in conjunction with steam boilers, and a purpose of my invention is the provision of an oil burning apparatus by means of which the intensity of the flame emanating from the burner is automatically controlled in accordance with the variance in pressure of steam in the boiler and in such manner that the relative proportions of oil and steam applied to the burner remain constant.

It is also a purpose of my invention to provide an apparatus including a burner constructed to utilize the steam in effecting a super-heating of the oil within the burner whereby a far more efficient combustible mixture is secured.

I will describe one form of oil burning apparatus embodying my invention, and will then point out the novel features thereof in claims.

In the accompanying drawings:

Figure 1 is a view showing in vertical section one form of apparatus embodying my invention.

Figure 2 is a vertical sectional view taken on the line 2—2 of Figure 1.

Referring specifically to the drawings, in which similar reference characters refer to similar parts, my invention in its present embodiment comprises a cylindrical casing designated generally at K and including sections 15 and 16 each of which is of semi-cylindrical form. These sections are secured together by means of rods or bolts 17, the section 15 being formed upon its inner side with cylindrical projections 18 arranged adjacent the opposite ends of the section with the projections spaced apart in parallelism and rigidly supported by flanges 19 formed on the section 16. Each projection is divided transversely by means of a partition 20 into

two chambers. The chambers in the upper projection are designated at S and D, respectively, and are adapted to communicate with each other through the medium of a port 21 formed in the partition 20 and controlled by a valve V. The chambers in the lower projection are designated at S' and D', respectively, and are likewise in communication with each other through the medium of the port 22 formed in the partition 20 and controlled by a valve V'.

The chamber S constitutes an oil supply chamber to which oil is adapted to be supplied by a pipe P connected to an oil reservoir. The chamber S' constitutes a steam supply chamber to which steam is applied through a pipe P' connected to a boiler (not shown) for which the oil burning apparatus is designed. The chambers D and D' constitute oil and steam dispensing chambers, respectively, the passage of oil and steam to these chambers being controlled through the medium of the valves V and V'. As clearly shown in Figure 1, the seat for the valve V is disposed reversely with respect to the seat for the valve V', the two valves working upon opposite sides of the partitions 20 and fixed to the ends of stems or rods R and R', respectively, slidably mounted through stuffing boxes 23. To effect simultaneous opening and closing of the valves V and V', a lever L is provided which is fulcrumed at a point medial of its ends as indicated at 24 on the end of a standard 25 bolted to the casing K. This lever is provided at its ends with slots 26 in which work pins 27 fixed to the rods R and R'. This arrangement effects the forward movement of the valve V and the rearward movement of the valve V' when the lever L is rocked in one direction and a reverse movement of the valves when the lever is rocked in the other direction. Actuation of the lever is effected through the medium of the rod R' which is continued to constitute the rod of a piston 28 mounted in a cylinder 29 sustained on a suitable base 30. Steam is supplied to the cylinder 29 through a pipe 31 which is adapted to be connected to the boiler before mentioned, and under the

tion of the steam the piston is moved to the right as when viewed in Figure 1. This piston is normally urged to a point medial of the ends of the piston by means of a coiled 5 expandible spring 32 embracing the piston rod within the cylinder as clearly shown.

The oil burning apparatus includes a burner designated generally at B and which in the present instance is made up of two 10 like sections 33 and 34 provided with flanges at their confronting edges through which bolts 35 extend for securing the sections together in the form of a rectangle as clearly shown in Figure 2. As shown in Figure 15 the outlet end of the burner is formed with oppositely inclined walls, the confronting edges of which are arranged in spaced relation to provide an outlet port 36. Secured to the flanges and between the sections 20 of the burner is a dividing partition 37 preferably formed of copper and arranged to divide the burner into an upper and oil chamber 38 and a lower and steam chamber 39. These chambers are at all 25 times in communication with the dispensing chambers D and D', respectively, through the medium of pipes 40 and 41, respectively.

In the operation of the apparatus, the 30 burner B is adapted to be arranged within the fire box of a boiler, with the pipe 31 connected to the boiler to supply steam to the cylinder 29 as previously described. With no steam pressure in the boiler, the piston 35 occupies the medial position shown under the action of the spring 32, and in this position the valves V and V' are in full open position so as to allow the maximum supply of oil and steam to the burner B, the oil and 40 steam passing from the supply chambers S and S' through the ports 21 and 22 into the dispensing chambers D and D' and thence through the pipes 40 and 41 into the chambers 38 and 39. The oil and steam 45 leave the burner through the port 36, an intermixing of the two occurring at the forward end of the partition 37. As the steam traverses the chamber 39 the partition 37, which is preferably formed of copper, becomes intensely heated so that as the oil 50 is introduced into the upper chamber 38 it falls on the partition and is thus vaporized so that it finally leaves the burner in the form of a vapor and in combining with the 55 steam produces a highly efficient combustible mixture. As the pressure of steam in the boiler increases it, of necessity, increases the pressure in the cylinder 29 thus moving the piston 28 to the right against 60 the tension of the spring 32. Under this action the rod R' is moved forwardly so as to close the valve V', and as the lever L is operatively connected to the rod R', it is evident that the valve V will likewise be 65 moved to closed position. By virtue of the

valve operating mechanism the degree of movement of the two valves is the same so that as the supply of oil to the burner is decreased the supply of steam is decreased in the same proportion thus maintaining at all times a proper mixture of oil and steam. Should the pressure of steam in the boiler decrease it will be clear that the reverse operation takes place so as to move the valves to open position and thus increase the supply of oil and steam to the burner.

Although I have herein shown and described only one form of oil burning apparatus embodying my invention, it is to be understood that various changes and modifications may be made herein without departing from the spirit of the invention or the spirit and scope of the appended claims.

What I claim is:

1. An oil burner comprising two half sections, each having an inclined end terminating at its free edge short of the plane of the free edges of the remaining walls of the section, means whereby the two sections may be secured in edge to edge superposed relation, a partition plate clamped between the confronting edges of said sections and terminating at its one end short of the confronting edges of the inclined ends of the sections, whereby an outlet for the casing 85 is provided between the confronting edges of the inclined ends and the casing is divided into an upper compartment and a lower compartment, said compartments having restricted communication with each other at the juncture of each with the outlet port.

2. An oil burner comprising a casing having an end consisting of upper and lower oppositely inclined sections merged at their remote edges into horizontal walls and terminating short of each other at their proximate edges to provide an outlet port, and a horizontal partition plate extending within the casing in a plane intersecting the outlet port midway between the upper and lower walls of the latter, said partition plate terminating at its one end short of the inner end of the outlet port, whereby the casing is divided interiorly into an upper compartment and a lower compartment, said compartments having restricted communication with each other and with the port, and said compartments being adapted respectively for connection with means for feeding oil and steam thereto.

3. An oil burning apparatus comprising a casing having an end consisting of upper and lower oppositely inclined sections merged at their remote edges into horizontal walls and terminating short of each other at their proximate edges to provide an outlet port, and a horizontal partition plate extending within the casing in a plane intersecting the outlet port midway between the upper and lower walls of the latter, said par- 125

tion plate terminating at its one end short of the inner end of the outlet port, whereby the casing is divided interiorly into an upper compartment and a lower compartment, said compartments having restricted communication with each other and with the port, means for supplying oil to said upper

compartment, means for supplying steam to said lower compartment, and means for controlling both of said supply means to maintain constant the ratio of the quantities of oil and steam supplied to said compartments. 10

WALTER EMILE FISHER.
